UNITED STATES PATENT OFFICE.

FRED RUDOLPH RUMPEL, OF RICHLFIELD, IDAHO.

FURROW-MARKER.

1,302,714.

Specification of Letters Patent.

Patented May 6, 1919.

Application filed November 4, 1918. Serial No. 261,035.

To all whom it may concern:

Be it known that I, FRED R. RUMPEL, a citizen of the United States, residing at Richfield, in the county of Lincoln and State 5 of Idaho, have invented certain new and useful Improvements in Furrow-Markers, of which the following is a specification.

This invention relates to harrows and diggers, and more especially it is a furrow 10 marker which when drawn across the field is adapted to mark the same with lines along which it is to be subsequently plowed.

The invention consists of a simple machine mounted on wheels and having markers or shovels spaced a distance equal to 15 that which it is intended to have between the furrows, and means for raising and lowering the shovels so that they can be put out of use, as when the machine is drawn to the 20 field and back, or can be put into use when the machine is at work.

Details of structure are set forth in the following specification and claims, and shown in the drawing, wherein—

25 Figure 1 is a side view and

Fig. 2 is a plan view of the machine complete.

Fig. 3 is a perspective view showing one of the pivots.

30 The main axle 1 is preferably made of angle iron carrying spindles 2 at its extremities on which are journaled a pair of wheels 3. The tongue 4 is secured upon the axle at its center and braced by hounds 5, and the seat 35 6 is mounted in a standard 7 rising from the tongue. The numeral 8 designates a double-tree to which the draft is applied, and the singletrees are attached to it as usual.

Secured to the upright lower leaf of the 40 axle are plates 10 each having a pair of outstanding ears 11 between which on a bolt 12 is pivoted an eye 13 at the front end of a bar 14. The rear ends of the several bars are secured as by rivets 15 across a beam 16 45 which also may be of angle iron, as seen in Fig. 1. Standards 17 are secured to the rear face of said beam and carry shovels or markers 18 at their lower ends, and braces 19 connect the standards with their respective bars 50 to maintain these elements in rigid relation and at about right angles to each other. The shovels or markers are spaced a distance apart equal to the distance which it is desired to have between the furrows in the field being treated.

Pivoted at 20 to one side of the tongue 4 is a lever 21 having a thumb latch 22 actuating a dog 23 which engages a toothed sector 24 carried by the tongue, so that the lever will remain in whatever position it is 60 adjusted by the operator who can reach it from his position in the seat 6. The lever is connected with the beam 16 by a rod 25, the rod being attached to a lever at the point 26 above the pivot 20, and 65 the lever is also connected with the beam by a lower rod 27, attached to the lower end of the lever at the point 28. The rear ends of both these rods are connected with the beam 16 at the point 29 as best seen in Fig. 2. 70 The result of this construction is that when the lever is moved in one direction or the other, the entire beam 16 and all parts attached thereto are raised around the pivots 12 or lowered. Thus the shovels or markers 75 18 are caused to rise out of the ground or descend into it according to the wishes of the operator.

While I have described this device as intended for scratching the earth, it is possible that the shovels 18 could be in the form of cultivator blades which will enter the earth and do cultivating between rows or furrows, but in that case the machine would have to be driven over ground which is already planted and would of course have to be properly guided so that the shovels would come between the furrows instead of into them.

The foregoing description and drawings 90 have reference to what may be considered the preferred or approved form of my invention. It is to be understood that I may make such changes in construction and arrangement and combination of parts, materials, dimensions, etc., as may prove expedient and fall within the scope of the appended claims.

Having fully described my invention, what I claim as new and desire to secure by Letters Patent, is:—

1. The herein described land marker comprising an axle mounted on wheels and having a tongue projecting forward from it, a plurality of bars pivoted at their front ends 105 to said axle, a beam rigidly connecting their rear ends, a plurality of standards extending from this beam and carrying shovels, a lever pivoted to and crossing the tongue, a seat rising from the latter adjacent the lever, 110

and connections between the lever above and below its pivot and the beam for raising and lowering the latter.

2. The herein described land marker comprising an axle mounted on wheels and having a tongue projecting forward from it, a plurality of bars pivoted at their front ends to said axle, a beam rigidly connecting their rear ends, a plurality of standards extending from this beam and carrying shovels, a toothed sector fast on said tongue, a lever pivoted at the center of said sector and crossing the tongue, a thumb latch on the lever engaging the teeth of the sector, a rod connecting the lever at a point above its pivot with said beam, and a second rod connecting the lever at a point below its pivot with said beam, the whole for use substantially as described.
- 20 3. In a land marker, the combination with an axle of L-iron having spindles at its extremities, wheels mounted thereon, a tongue extending forward from said axle, and a hand lever pivotally mounted on said tongue; 25 of a series of plates connected with the rear leaf of said axle and each having a pair of

projecting ears, a series of bars having eyes at their front ends passing between the ears of a pair, pivot bolts through said ears and eyes, a beam connecting the rear ends of said bars, standards extending rigidly from said beam and carrying markers, and connections between said beam and lever, for the purpose set forth.

4. In a land marker, the combination with an axle having wheels mounted on its extremities, a tongue projecting forward from said axle and a lever pivoted to said tongue; of a series of standards carrying markers, a transverse beam by which said standards are supported, a plurality of bars connected to said beam and leading to the axle, pivotal connections between their front ends and said axle, braces connecting the bars with the standards, and connections between the beam and lever, for the purpose set forth.

In testimony whereof I affix my signature in presence of two witnesses.

FRED RUDOLPH RUMPEL.
